(Continued)

Primary Examiner — Daniel Bui(74) *Attorney, Agent, or Firm* — Jones Robb, PLLC(57) **CLAIM**

The ornamental design for a cable connector, as shown and described.

DESCRIPTION

FIG. 1 is a perspective view of a cable connector of my new design.

FIG. 2 is another perspective view of thereof.

FIG. 3 is a front view thereof.

FIG. 4 is a bottom view thereof.

FIG. 5 is a left side view thereof.

FIG. 6 is a top view thereof; and,

FIG. 7 is a right side view thereof.

The shade lines in the Figures show contour and not surface ornamentation.

Portions of the figures depicted in broken lines show environmental structure and form no part of the claimed design.

1 Claim, 2 Drawing Sheets(56)
